[57] CLAIM

The ornamental design for a lunch pail or similar article, substantially as shown and described.

DESCRIPTION

FIG. 1 is a side elevational view of a lunch pail or similar article showing my new design, both sides being identical.

FIG. 2 is a top plan view thereof.

FIG. 3 is a bottom view thereof.

FIG. 4 is an end elevational view thereof, both ends being identical.

*Fig. 1**Fig. 2**Fig. 3*
